PROCESS OF CARBONIZING SOLID VEGETATION

Filed June 22, 1925

ATTORNEY

UNITED STATES PATENT OFFICE

WALLER CROW, OF CHICAGO, ILLINOIS, ASSIGNOR TO DITTLINGER-CROW PROCESS COMPANY, OF NEW BRAUNFELS, TEXAS, A CORPORATION OF TEXAS

PROCESS OF CARBONIZING SOLID VEGETATION

Application filed June 22, 1925. Serial No. 38,687.

This invention relates to modification in the physical condition of materials, more particularly in the association and dissociation control thereof brought about hereunder by reaction promotion therebetween.

This invention has utility especially for the utilization of by-products in commerce and industry of carbon containing materials, but in practice may even be adopted primarily in stead of for by-product operations.

Referring to the drawings:

Fig. 1 is an elevation, with parts broken away, of an installation embodying the invention; and

Fig. 2 is a section on the line II—II, Fig. 1, looking in the direction of the arrow.

Motor 1 may by speed reduction gearing 2 serve to rotate vertical shaft 3 in structure 4. Above this structure 4, there is disclosed chamber 5. To the upper region of this chamber 5 leads hopper 6 from supply conveyor 7. This hopper 6 extends to valve or discharge device 8 for dumping the material accumulating in the hopper 7 upon spiral conveyor 10 in the chamber or retort 5. The direction of rotation of this conveyor 10 on the shaft 3 is for a gradual descent of the material for discharge by chute 11 to hopper 12 having normally closed valve or wings 13.

The screw conveyor 10 is in the upper portion only of this retort chamber 5. In this chamber 5, below the conveyor 10, is platform 14 carrying upstanding fingers 15. Mounted on the shaft 3 above this platform or partial partition 14 are radiating arms 16 carrying depending projections 17 extending between the projections or fingers 15. More or less sub-divided or granular material as supplied by the conveyor 7 and delivered to the conveyor 10 for discharge on the platform 14, is

acted upon by these prongs 15, 17, for breaking up or disturbing any tendency to caking. The material as thus agitated or plowed by this revolving macerator is discharged through central opening 18 in the platform or partition 14 to continue its progress downward in the chamber 5.

Boiler 19 has furnace 20 to serve as a steam generator for delivering steam by pipe 21 to superheater 22 where furnace 23 is effective

for building up the superheat of the steam as supplied by the steam line 21. This superheated steam from the superheater 22 is conducted by line 24 past valve 25 to duct 26 extending to ring 27 having openings 28 in the lower portion of the chamber 5.

Additionally, from this duct 26 extends branch 29 having additional openings 30 inward about the chamber 5, below, as well as above the partition 14 and even into the region of the conveyor 10. This superheated steam is delivered

into the chamber 5 at approximately atmospheric pressure or say slightly over fifteen pounds absolute pressure. In practice, the superheat of the steam is to a degree in excess of 300° F. and even above 600° F. at pressure

for initial superheat say 100 lbs. gauge or 115 lbs. absolute. The variation herein may be made to respond to the conditions or work to be performed, as well as the material upon which the treatment is to be effected. For excessive virulence, it is desirable that the superheat be at the high points, say in the range of 600° F. or over.

The superheated steam as released through the tuyère openings 28, 30, to approximately atmospheric pressure brings about a temperature drop with a simultaneous increase in the degree of superheat. This expansion is independently of doing work and there should, accordingly, be a retention of the total heat,

which has been worked out in Molliere steam tables. In the instance of say 600° F. initial superheat, the drop in temperature due to expansion is approximately 22° F. with the resultant superheat approximating 688° F. This expansion building up of superheat in this instance is with but 25% of the degree of temperature drop as to the superheat gain because the superheat increase is 88° or four times the 22° expansion temperature drop.

The virulence is found of greater activity in the region where the temperature drop is low relatively to the superheat gain. The term "virulence" is used herein in the sense as being very active in doing injury or to disturb, but not in the sense of a poison. This percentage of temperature drop is lower, the greater the temperature.

It is desirable in the operation of the chamber

ber 5, that such be lined to resist chemical attack. While the vessel or chamber 5 may be of iron or steel for some materials, in the instance of this disclosure the vessel is provided 5 with refractory lining 31 of fire brick or porcelain.

While the reactions as effected by the superheated steam have a degree of virulence, especially in the realm of approximate combustion temperature for the material to be acted upon, it is found the rate of reaction 10 may be many times multiplied with a much lower temperature in the instance of providing accelerators effective by their presence in promoting the treatment hereunder. To this end, the lining 31 is provided with chambers 32, 33, 34, in communication with the chamber 5. These chambers may be charged with the same materials or different materials 15 according to the treatment to be effected. The promotion of reaction in the material as well as the rate of bringing such about is very noticeably modified by the introduction of broken limestone into the chambers 32. 20 In the event the substance treated, or the limestone has not therein a material quantity of iron, additional acceleration effect may be had by the placing of an iron carbonate or iron carbonate containing ore in association 25 with the limestone fragments in the chamber 32 or preferably in the chamber or portion of the chambers 33, 34. Carbonate as used herein refers to such weathered or partially weathered product as has undergone incomplete oxidation. Brown hematite has been 30 used. These carbonates are preferably in a sub-divided state. The limestone may be up to one-half inch size and likewise with the iron ore. Other salts than carbonates have 35 been found to answer, as sulphates. While iron oxid has been found acceptable, manganese oxid has been found to answer as also zinc oxid. However, it is primarily desired 40 that there be present calcium or calcium magnesium as found in dolomite, as hereinbefore referred to under limestone. In lieu of the limestone, magnesium carbonate or sulphate 45 as well as barium carbonate and sulphate have been used. 50 In the operation hereunder, volatile materials are driven off from the substance treated, as sawdust, bark, wood trimmings, as from lumber plants, or special characters of timber. This treatment is of worth for 55 bringing about reactions upon garbage, coal, vegetation in the green or dried, and even fruit and vegetables, whether dried, fresh or semi-dried.

Flue 35 from above the chamber 5 may 60 take off fumes. Fan 36 is controllably operated by motor 37 and may accelerate draw off draft of the fumes in this duct 35 as desired. This duct 35 may deliver to condenser 38 with tailing lines 39 therefrom for gathering 65 the material in receivers 40. Supple-

mental mains or flues 41, 42, may take off other volatile materials and pass such to condensers 43, 44, for gathering in receivers 45, 46. The residue of material from this treatment is discharged by the chute or hopper 12 and may in the instance of vegetation or wood be a char of value as a pigment or filler according to the purity of the carbon. 70

This char is produced independently of operation of the chamber 5 at an ignition or combustion temperature. The atmosphere is one effecting an attack independently of the production of carbon-dioxide. Experience has been in the treatment of carbon containing materials that resulting products have been obtained with total carbon content thereof in excess of the carbon content of the material directly treated. This leads applicant to believe that the carbon in the 80 carbonate has been associated either synthetically or in the breaking down as united in the production of oil or other carbon containing products in the treatment of the hydrogen and carbon containing material. 85

The action upon the limestone is one tending to convert such into a quick lime and with other conditions of superheat even to a hydrate. It, therefore, becomes a more or less oxidized caustic. The reaction on the iron ore 90 is also one tending to a pure iron oxide. Accordingly, while these promotion agents are incidental in the matter of treatment as by-products, they have a value and in the operations hereunder along the chamber, the oxide 95 may be re-converted into a carbonate. To this end, the material treated is of excessive carbon content or there must be a supply of carbon-dioxide. There is value incidental to 100 this re-carbonating in that the quick lime or hydrate material may be molded into form and the carbonating thereof result in an artificial marble. 105

The operation in the treatment of vegetation, coal, or wood, may be one directed for 110 the production of a motor fuel; or for the production of a fixed gas for illumination or power purposes. The controls are possible for even operating upon petroleum and the condensed products may be controlled for the desired fractions or cracking. The non-volatile products, as residues, may be controlled according to the degree of extraction after the driving off. Scrubbers 47 may be introduced in the vapor main 41 as desired 115 for gathering up by-products there, as ammonia, or other material. 120

In the operation hereunder, due to the use 125 of the superheated steam there seems to be such virulence of this hydrogen and oxygen and such special condition thereof promoted that the hydrogen has imparted there-to unusual properties approximating those found for helium, if not really actual produc- 130

tion of helium a non-combustible gas collected in the globules of the condensate.

The range of utility due to the possibility of operating at low temperature and thereby conserving all elements, as well as synthesizing for desired purposes, gives this mode of treatment exceptional value in wide ranges of industrial operations.

What is claimed and it is desired to secure by Letters Patent is:

- 10 1. The carbonization of vegetable matter comprising acting upon the matter in a solid state with superheated steam by exposing in the presence of the matter to be acted upon by a solid substance including an alkaline earth base reacting material to said steam as supplied to such presence including dissociated hydrogen and oxygen, maintaining the solid state matter separate from and out of 20 solid contact with the solid state of the substance during the steam reaction therebetween, and effecting removal of volatiles from the matter acted upon by maintaining a flow of said steam past the matter.
- 25 2. The carbonization of vegetable matter comprising acting upon the matter with superheated steam by exposing in the presence of the matter to be acted upon by solid substance including limestone and iron ore to 30 said steam as supplied to such presence including dissociated hydrogen and oxygen, maintaining the solid state matter separate from and out of solid contact with the solid state of the substance during the steam reaction therebetween, and effecting removal of 35 volatiles from the matter acted upon by maintaining a flow of said steam past the matter.

In witness whereof I affix my signature.
WALLER CROW.
